UNITED STATES PATENT OFFICE.

JULIAN P. HENDRICKSON, OF CHEHALIS, WASHINGTON.

MARINE PROPULSION.

Application filed May 18, 1925. Serial No. 31,138.

To all whom it may concern:

Be it known that I, JULIAN P. HENDRICKSON, a citizen of the United States of America, residing at Chehalis, county of Lewis, and State of Washington, have invented certain new and useful Improvements in Marine Propulsion; and I do hereby declare that the following is a full, clear, concise, and exact description of the invention, such as will enable others skilled in the art to which it appertains to make and use the same.

This invention relates to improvements in marine propulsion, having for an object to provide a novel form of motive means for marine vehicles whereby with initial propulsion or operation of the same through a body of water at proper speed, a portion of said water will be injected into the motive means with force or velocity sufficient to operate the same independently of any extraneous or auxiliary motive means, hence, permitting such vehicle to be successfully driven through the power so generated.

It is likewise an equally important object of the invention to provide a motive means for marine propulsion utilizing a novel form and arrangement of water or fluid injector means, whereby a portion of the water through which the marine vehicle is being driven will be taken up by said injector means during movement of the vehicle and conveyed with sufficient force or power for discharge onto the rotor of a suitable turbine motive means whereby to effect the desired drive of the propeller carrying shaft; such injector means being so arranged as to permit of the transmission of either forward or reverse rotary motion to said propeller carrying shaft.

Another and equally important object of the invention is to provide the improved motive means with a form of water or fluid urging means, functioning to draw a sufficient quantity of water to the injector means to ensure proper operation of the motive means supplied thereby, irrespective of rolling or other body displacing movement of the equipped vehicle.

Other objects of the invention will be in part obvious, and in part pointed out hereinafter.

In order that the invention and its mode of operation may be readily understood by persons skilled in the art, I have in the accompanying illustrative drawings, and in

the detailed following description based thereupon, set out one possible embodiment of the same.

In these drawings:—

Figure 1 is a fragmentary horizontal section through a boat equipped with the invention;

Figure 2 is a fragmentary elevation of the same, the intermediate portion of the boat being broken away and shown in section;

Figure 3 is an enlarged vertical section through one of the water turbines for propelling the boat; and,

Figure 4 is a fragmentary detail in vertical section, taken on the line 4—4 of Figure 3 looking in the direction which the arrows point.

Having more particular reference to the drawings, in connection with which like characters of reference will designate corresponding parts throughout, the hull of the equipped boat is indicated herein in its entirety, by the numeral 1, it being noted in this connection that both the bow and stern portions of such hull are tapered, as indicated by the numeral 2, the stern portion of the hull being provided with a suitable propeller 3, carried upon the usual longitudinally disposed propeller shaft 4 extending through suitable water-tight packing into and through the boat hull, as is shown in the Figures 1 and 2, while a rudder or other steering medium 5 is likewise mounted adjacent the stern portion for obvious purposes.

Mounted in juxtaposed relation upon a suitable bed or support arranged upon the hull bottom is a plurality of rotary water or fluid turbines generally indicated herein by the numerals 6 and 7, the turbines 6 serving to transmit forward rotary motion to the propeller shaft 4 to which its rotor is connected, while the turbine 7 is adapted to transmit reverse rotary motion to said propeller shaft 4. In this connection, attention is directed to the fact that a portion of the propeller shaft 4 is extended through the casing of the turbine 6 and carries an immovable clutch segment 8 thereon, this clutch segment being adapted to be engaged by a shiftable or movable clutch element 9, operable through suitable means indicated by the numeral 10, such movable clutch element 9 being mounted for movement upon a shaft 11 extending from the

concentric portion of the turbine housing 7 and of course, being fixedly connected to the rotor thereof. Normally, it will be understood that the movable clutch element 9 is disengaged from the immovable clutch element 8 mounted upon the extended end of the propeller shaft 4 and hence, the uninterrupted or unimpeded transmission of forward rotary motion to such propeller shaft will be permitted. However, with engagement of the movable clutch element 9 with the immovable clutch element 8, the forward motion transmitting turbine 6 is rendered inoperative, while the reverse motion transmitting turbine 7 is rendered operative, thereby transmitting reverse rotary motion to the propeller carrying shaft 4.

With a view towards supplying the turbines 6 and 7 with motive power, a plurality of tubular injector devices 12 and 13 are provided, these injector devices tapering inwardly throughout their respective lengths and being fixedly supported within and disposed longitudinally of the boat hull 1; the rearward ends thereof communicating through elbow-like extensions 14 and 15, respectively, with the fluid or motive means intake ports of said turbines 6 and 7. The forward portions of the several injector devices 12 and 13 are formed with opposed outwardly curved necks or extensions 16 and 17, the ends of which open onto a tapered side 2 of the bow and stern portions of the boat hull 1, thus providing effectual water intake ports 18 for the same, which, as will be noted, are of substantially oval-shaped formation whereby to ensure of the passage of a sufficient volume or quantity of water thereinto and through their respective inwardly tapering injector devices 12 and 13.

To permit of effectual control of the discharge of water from the injector devices 12 and 13 by way of their respective elbow extensions 14 and 15 into the turbines 6 and 7 whereby the same may be caused to be selectively operated, valves are arranged in suitable casings 19 adjacent to and communicating with the inner extremities of such injector devices and are provided with suitable handles 20 to facilitate their operation.

At times during the passage or travel of the equipped boat through water, it will be appreciated that the same will be caused to roll by reason of various disturbances upon the water surface and in order that such rolling will not materially interfere with the intaking of water through the then functioning injector devices 12 or 13, I may and preferably do tap onto the inner portions of such devices 12 and 13 the opposite extremities of a substantially U-shaped pipe or conduit 21, connecting the intermediate portion of said conduit to a suitable T-coupling or similar means, such as indicated

by the numeral 22, to a suction creating motor operated pump 23. Thus, it will be understood that with the setting up of a vacuum or partial vacuum through the suction creating pump 23 in the inner ends of the injector devices 12 and 13, the particular injector devices then functioning will be caused to draw a quantity of water through its particular intake ports 18 for discharge into the casing of its respective turbine under velocity sufficient to ensure continued operation of the same.

An auxiliary motive means, preferably in form of a small internal combustion engine, indicated generally herein by the numeral 24, is mounted upon that bed carrying the turbines 6 and 7 within the boat hull and is connected to a suitable form of air compressor 25, which compressor in turn, is adapted to discharge air dispensed thereinto a suitable storage tank or reservoir 26 also supported upon and within the intermediate portion of the hull 1. An outlet conduit 27 is provided this reservoir 26 and communicates with the intermediate portion of a substantially U-shaped conduit 28, the free open extremities of which discharge into the adjacent portions of the inner ends of the several injector devices 12 and 13; suitable forms of manually operable valve means 29 being interposed in the several branches of the U-shaped conduit 28 in order that the control or passage of compressed air into the several injector devices 12 and 13 may be controlled or regulated at will by an operator.

It may be also noted at this point that the turbines 6 and 7 are provided with curved water discharging conduits 30 and 31, the lower or free curved end of the conduit 30 connected to the forward motion transmitting turbine 6 being disposed rearwardly of the hull 1, while the similar portion of the conduit 31 connected to the reverse motion transmitting turbine 7 is disposed forwardly of said hull 1, as is clearly shown in the Figure 2. Flap valves 32 are pivotally or hingedly connected to the open lower ends of the several water discharging conduits 30 and 31 and obviously, will prevent the passage or intaking of water into the casing of the particularly inactive turbine 6 or 7.

The modus operandi of the invention may be reviewed as follows:

To initially propel the equipped marine vehicle through a body of water at a speed sufficient to bring about injection of water under a force or velocity sufficient to set up operation of the main motive means, air of proper pressure is stored in the reservoir 26 through the motor 27 and the compressor 25 connected thereto. At this time, one of the hand operable valves 29 is opened, this depending upon the direction in which the equipped marine vehicle is to be driven. 130

Thus, if the vehicle is to be driven forwardly through a body of water, that valve 29 controlling communication with the injector device 12 is opened, thus permitting discharge 5 of air under pressure onto the rotor of the forward motion transmitting turbine 6, and hence, effecting rotation of the same in a forward direction whereby to similarly rotate the propeller carrying shaft 4 to drive 10 the vehicle or boat. When travel of the equipped boat through a body of water at the proper speed has been attained, the discharge of compressed air into the turbine 6 may be discontinued by closing the aforesaid 15 valve 29. At this time, the intake ports 18 of the respective branch extension 16 of the injector device 12 will have water passing therethrough and through said injector device under a pressure or force sufficient that 20 with its discharge by way of the elbow 14 into the turbine casing 6, the rotor of such turbine will be caused to rotate at a velocity sufficient to maintain successful operation of the propeller shaft 4 and its propeller 3. By 25 controlling the passage way for the incoming water by the valve 19 of the injector device 12, it will be understood that the speed of the forward motion transmitting turbine 6 may be regulated at will by an operator. 30 If desired, rotation of the turbine may be completely discontinued merely by fully closing this particular valve. When it becomes desirable to propel the equipped boat through a body of water in a reverse direction, the 35 control valve 19 of the injector means 12 is of course completely closed, and at this time, that hand operable valve 29 communicating with the injector device 13 is opened whereby to permit the flow of a sufficient quantity 40 of compressed air through its particular branch of the conduit 28 into said injector device 13 and from thence, onto the rotor of the reverse motion transmitting turbine 7 through the elbow 17. In this way, it is 45 manifest that reverse rotary motion will be imparted to the rotor of the turbine 7 and at this time, the movable clutch element 9 is engaged in the immovable clutch element 8 upon the propeller shaft 4 through the shifting mechanism 10. Consequent upon this 50 connection, reverse rotary motion will be transmitted to the propeller shaft 4 whereby to effect functioning of the propeller 3 in a manner to impart reverse travel to the 55 equipped boat. As in the case of initially driving the equipped boat in a forward direction, with travelling of the boat in a reverse direction for a time sufficient to attain proper speed, the hand controlled valve 19 60 communicating with the injector device 13 is gradually opened, while the hand controlled valve 29 communicating with said injector device 13 is closed. With opening of the 65 control valve 19, just mentioned, it will be understood that a flow of water through the injector device 13 from its port 18 of the oppositely curved extension or branches 17 will be effected and the force or velocity at which this water passes through the injector device 13, which of course is increased by its 70 inwardly tapered formation, will be sufficient with discharge onto the rotor of the reverse motion transmitting turbine 7 to rotate the same at a velocity whereby to maintain successful rotation of the propeller shaft 4 75 in its reverse direction and thus maintain travel of the boat in a corresponding direction through the body of water. The speed of this reverse drive or movement of the boat may, of course, be regulated by an operator, at will, merely by corresponding adjustment of the control valve 19 of said injector device 13. 80

As hereinbefore stated, there will be times during travel of the boat through a body of water when means will be desired or required for maintaining a constant flow of water through either of the injector devices 12 and 13 and for accomplishing these ends, it is only necessary that the motor 23 of the suction creating pump be started whereby to produce a partial vacuum or suction in the particular injector device 12 or 13 through which water is to be passed. By setting up this suction in either of the injector devices, 85 it will be appreciated that a continuous flow of water through the same will be urged and that such flow will be sufficient, at all times, to maintain proper operation of either of the turbines 6 or 7. 90

Manifestly, the construction shown is capable of considerable modification, and such modification as is within the scope of my claims, I consider within the spirit of my 95 invention. 100

I claim:

1. In a marine vehicle, injector means therein opening onto the bow and stern portions of the same, fluid operable means communicating with said injector means and adapted to be selectively connected to the vehicle propeller shaft, a source of compressed air within the vehicle connected to the inner ends of each of said injectors, means for supplying compressed air to said source and maintaining the pressure thereof, and other means connected to the inner portions of said injectors for maintaining a partial vacuum therein, at times. 110
2. In a marine vehicle, injector means arranged longitudinally therein opening onto the bow and stern portions of the same, fluid operable means adapted to be selectively connected to the vehicle propeller shaft, a source of compressed air in the vehicle, a valved discharge pipe communicating with said source of compressed air and the inner ends of said injectors, means connected to the inner portions of the injectors for maintaining a partial vacuum therein, at times, 115
3. In a marine vehicle, injector means arranged longitudinally therein opening onto the bow and stern portions of the same, fluid operable means adapted to be selectively connected to the vehicle propeller shaft, a source of compressed air in the vehicle, a valved discharge pipe communicating with said source of compressed air and the inner ends of said injectors, means connected to the inner portions of the injectors for maintaining a partial vacuum therein, at times, 120
4. In a marine vehicle, injector means arranged longitudinally therein opening onto the bow and stern portions of the same, fluid operable means adapted to be selectively connected to the vehicle propeller shaft, a source of compressed air in the vehicle, a valved discharge pipe communicating with said source of compressed air and the inner ends of said injectors, means connected to the inner portions of the injectors for maintaining a partial vacuum therein, at times, 125
5. In a marine vehicle, injector means arranged longitudinally therein opening onto the bow and stern portions of the same, fluid operable means adapted to be selectively connected to the vehicle propeller shaft, a source of compressed air in the vehicle, a valved discharge pipe communicating with said source of compressed air and the inner ends of said injectors, means connected to the inner portions of the injectors for maintaining a partial vacuum therein, at times, 130

and valves adjacent the inner ends of said injectors controlling communication between the same and said fluid operable means.

3. In a marine vehicle, injector means supported therein and arranged longitudinally of the same, said injector means comprising tubular bodies tapering inwardly throughout their respective lengths and having oppositely curved extensions formed on their outer ends opening onto the bow and stern portions of the vehicle, means for controlling the passage of fluid to said injector means, fluid operable means in the vehicle communicatable with said injector means and adapted to be selectively connected to the propeller carrying shaft of the vehicle, a source of compressed air within the vehicle, valved means connecting said source of compressed air with the inner ends of said injectors, and other means communicating with the inner portions of the injectors for maintaining a partial vacuum therein.

4. In a marine vehicle, fluid injector means arranged therein and extending longitudinally of the same to points intermediate of the body of the vehicle, said injector means tapering inwardly throughout their respective lengths and having oppositely curved branch extensions formed upon their outer ends opening onto the opposite sides of the bow and stern portions of the vehicle, valves means for controlling the passage of fluid through said injector means, fluid oper-

able means in the vehicle communicating with said injector means adapted to be selectively connected to and to transmit rotary motion to the vehicle propeller shaft, and auxiliary motive means in the vehicle communicatable with the inner ends of said injector means.

5. In a marine vehicle, injector means arranged therein and extending longitudinally through the same, said injector means each comprising tubular members tapered inwardly throughout their respective lengths and having oppositely curved branch extensions carried on their outer ends opening onto the opposite sides of the bow and stern portions of the vehicle, valve means for controlling the passage of fluid through said injector means, fluid operable means in the vehicle communicatable with said injector means, one of said fluid operable means being permanently connected to the vehicle propeller shaft and the other thereof being adapted to be detachably connected to said propeller shaft, air compressing means within the vehicle, a reservoir receiving such air from said air compressing means and communicatable with the inner ends of said injector means, and suction creating means in the vehicle communicating with the inner ends of said injector means.

In witness whereof I have hereunto set my hand.

JULIAN P. HENDRICKSON.
